UNITED STATES PATENT OFFICE

ROBERT H. COWDERY, OF GENEVA, OHIO, ASSIGNOR TO THE AMERICAN FORK & HOE COMPANY, A CORPORATION OF OHIO

DESIGN FOR A FISHING ROD

Application filed August 22, 1927. Serial No. 23,166. Term of patent 14 years.

To all whom it may concern:

Be it known that I, ROBERT H. COWDERY, a citizen of the United States, residing at Geneva, in the county of Ashtabula and State of Ohio, have invented a new, original, and ornamental Design for Fishing Rods, of which the following is a specification, reference being had to the accompanying drawing, forming part thereof.

Fig. 1, is a side elevational view of fragments of a fishing rod showing my new design; the showing of certain intermediate parts being omitted.

Fig. 2, is a similar view of the end of the rod taken at right angles to that of Fig. 1.

Fig. 3, is an elevational view of the butt end of the rod of Fig. 1, taken at an angle of 45° relative thereto.

Fig. 4, is an opposite end view of the rod looking in the direction of the tip.

I claim:

The ornamental design for a fishing rod, substantially as shown.

ROBERT H. COWDERY.
